UNITED STATES PATENT OFFICE

170,615

COMBINED JARS AND RACK THEREFOR

Edward Troha, Miami, Fla.

Application October 6, 1952, Serial No. 21,706

Term of patent 14 years

(Cl. D58—26)

To all whom it may concern:

Be it known that I, Edward Troha, a citizen of the United States, residing at Miami, county of Dade, State of Florida, have invented a new, original, and ornamental Design for Combined Jars and Rack Therefor, of which the following is a specification, reference being had to the accompanying drawing, forming a part hereof.

Fig. 1 is a front elevational view of combined jars and rack therefor, showing my new design.

Fig. 2 is a side elevational view thereof.

Fig. 3 is a cross-sectional view thereof, taken on the line 3—3 of Fig. 2.

I claim:

The ornamental design for combined jars and rack therefor, as shown.

EDWARD TROHA.
